UNITED STATES PATENT OFFICE

WILLIAM E. A. PIPHER AND ALVIN E. PIPHER, OF PARKERS LANDING, PENNSYLVANIA

OIL AGITATOR

Application filed July 18, 1931. Serial No. 551,806.

This invention relates to an oil agitator for use in increasing the production of old oil wells and maintaining the production of new wells.

As is well known to those skilled in the art more oil can be bailed from an old well than can be obtained by pumping. This is due to the fact that the bailer, when moved up and down through the oil stirs it thoroughly and washes the rock, thereby allowing the oil to flow more freely into the well. As a means for increasing flow some operators have drilled small holes part way through the ball in the standing valve so that when the hole in the ball turns to the right position it allows a jet of oil to shoot back into the well so as to stir the oil in the well. At best this method is very unreliable.

It is an object of the present invention to provide a positive agitating means for the oil, said means being actuated by the movement of a valve which, in turn, is operated by the suction of oil through the working barrel.

Another object is to use an agitating device located outside of the tubing where it can readily churn or agitate the oil and keep the rock free from paraffin.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings:

Figure 1 is an elevation of the device attached to a working barrel in place of the usual perforated tubing anchor.

Figure 2 is an elevation view at right angles to Figure 1.

Figure 3 is an enlarged section on line 3—3, Figure 2.

Figure 4 is an enlarged section on line 4—4, Figure 2.

Figure 5 is an enlarged section on line 5—5, Figure 1.

Figure 6 is an enlarged section on line 6—6, Figure 1.

Referring to the figures by characters of reference, 1 designates the lower end of a working barrel engaged by a coupling 2 which supports the tubing 3 forming the body portion of the present invention. A head 4 joins the tubing to the sleeve and has a central countersunk bore 5 about which is arranged a series of small openings or ports 6. The space between head 4 and working barrel 1 forms a valve chamber 7 in sleeve 2.

The lower end of tubing 3 is engaged by a collar 8 which supports a spacing ring 9 loosely mounted on the tubing. A pin 10 limits the movement of this ring. Another spacing ring 11 is carried by head 4 beneath sleeve 2.

Longitudinal slots 12 are formed in the tubing 3 and extending loosely through them is a diametrical cross bar 14 the ends of which are fastened to an agitating ring 15 slidable on tubing 3. This ring supports a coiled spring 16 extending loosely around tubing 3 and slidable thereon.

A flat valve 17 normally closes the ports 6. A rod 18 is secured at its upper end to this valve and extends downwardly through bore 5. The lower end of the rod is attached to bar 14.

The tubing is adapted to be substituted for the perforated tubing usually attached to the lower end of the working barrel. During the alternate or upstrokes of the working valve (not shown) the oil will be sucked through slots 12 and upwardly through ports 6, at the same time lifting the flat valve 17. Thus the bar 14 and ring will be elevated along tubing 3 and correspondingly move the spring 16. When the suction ceases and the valve 17 drops the rod 18 and the parts connected thereto will also drop.

Spring 16 and ring 15 will act to churn the oil and keep the rock washed thoroughly and while means other than a spring could be used as an agitator, it is preferred to employ a spring because it vibrates more readily and

thus acts better as an agitator than would rigid devices.

If preferred a flood hole 19 can be provided in head 4 although this is not necessary.

5. What is claimed is:

1. An oil agitator for attachment to the lower end of a working barrel, including a tubing having ports at its upper end and a slot in its wall, a valve normally closing the ports and liftable by suction in the working barrel, an agitator slidable along the outside of the tubing, and a connection between the valve and agitator, said connection working in the slot.

15. 2. An oil agitator for attachment to the lower end of a working barrel including a tubing having a port in its upper end, a valve normally closing the port and liftable by suction in the working barrel, an agitator operated by said valve, said agitator including

20. a ring slidable on the tubing, and a connection between the ring and valve, said tubing being slotted for the connection.

25. 3. An oil agitator for attachment to the lower end of a working barrel including a tubing having a port in its upper end, a valve normally closing the port and liftable by suction in the working barrel, an agitator operated by said valve, said connection including 30. a ring, a cross bar connected thereto and slidable in the tubing, a rod connecting the bar and valve, and an agitator on the ring and tubing.

35. 4. An oil agitator for attachment to the lower end of a working barrel including a tubing having a port in its upper end, a valve normally closing the port and liftable by suction in the working barrel, an agitator operated by said valve, said connection including 40. a ring, a cross bar connected thereto and slidable in the tubing, a rod connecting the bar and valve, and an agitating spring supported by the ring and slidable on the tubing.

45. 5. A structure for attachment to the lower end of a working barrel, a suction operated valve, and oil agitating means operated by the valve for working between said structure and the side wall of a well.

50. In testimony that we claim the foregoing as our own, we have hereto affixed our signatures.

WILLIAM E. A. PIPHER.
ALVIN E. PIPHER.
